(57) **CLAIM**

The ornamental design for a suction cup clip, as shown and described.

DESCRIPTION

FIG. 1 is a perspective view for a suction cup clip;

FIG. 2 is a rear planar view thereof;

FIG. 3 is a front planar view thereof;

FIG. 4 is a right-side elevational view thereof;

FIG. 5 is a left-side elevational view thereof;

FIG. 6 is a top end view thereof; and,

FIG. 7 is a bottom end view thereof.

The parts delineated in broken lines are not part of the claimed design.
